CLAIM

The ornamental design for a hay feeder, as shown and described.

DESCRIPTION

FIG. 1 is a perspective view of the hay feeder;
FIG. 2 is a side view of the hay feeder, where the opposing side view is identical;
FIG. 3 is a front view of the hay feeder, where the back view is identical;
FIG. 4 is a top view of the hay feeder;
FIG. 5 is a bottom view of the hay feeder; and,
FIG. 6 is a perspective view of the hay feeder with the roof thereof in an alternate position.

1 Claim, 6 Drawing Sheets
